(57) **ABSTRACT**

An exercise machine may include a deck, a motor housing incorporated into the deck, a lift motor located in the motor housing, and a cooling mechanism that cools the lift motor when the cooling mechanism is activated. An airflow pathway may be defined to direct air from the cooling mechanism to a location above the motor housing and on to a user of the exercise machine. The exercise machine may be configured such that upon beginning operation of the machine, substantially all of the airflow exhausts to the location above the motor housing. A mechanism may be provided to selectively alter a characteristic of the airflow after the exercise machine has begun operation.

COOLING SYSTEMS AND METHODS FOR EXERCISE EQUIPMENT

RELATED APPLICATIONS

This application is a continuation-in-part of U.S. patent application Ser. No. 15/639,935 filed on 30 Jun. 2017 and titled "System and Methods for Cooling Internal Exercise Equipment Components." U.S. patent application Ser. No. 15/639,935 is herein incorporated by reference for all that it contains.

BACKGROUND

Aerobic exercise is a popular form of exercise that improves one's cardiovascular health by reducing blood pressure and providing other benefits to the human body. Aerobic exercise generally involves low intensity physical exertion over a long duration of time. Typically, the human body can adequately supply enough oxygen to meet the body's demands at the intensity levels involved with aerobic exercise. Popular forms of aerobic exercise include running, jogging, swimming, and cycling among others activities. In contrast, anaerobic exercise typically involves high intensity exercises over a short duration of time. Popular forms of anaerobic exercise include strength training and short distance running.

Many choose to perform aerobic exercises indoors, such as in a gym or their home. Often, a user will use an aerobic exercise machine to have an aerobic workout indoors. One type of aerobic exercise machine is a treadmill, which is a machine that has a running deck attached to a support frame. The running deck can support the weight of a person using the machine. The running deck incorporates a conveyor belt that is driven by a motor. A user can run or walk in place on the conveyor belt by running or walking at the conveyor belt's speed. The speed and other operations of the treadmill are generally controlled through a control module that is also attached to the support frame and within a convenient reach of the user. The control module can include a display, buttons for increasing or decreasing a speed of the conveyor belt, controls for adjusting a tilt angle of the running deck, or other controls. Other popular exercise machines that allow a user to perform aerobic exercises indoors include elliptical trainers, rowing machines, stepper machines, and stationary bikes to name a few.

One type of treadmill is disclosed in World Intellectual Property Organization Publication No. WO/1989/07473 issued to Steven T. Sherrard, et al. In this reference, an exercise treadmill includes transverse modular components that are fixably yet slidably supported through T-slots in extruded side rails having inwardly opening T-slots. Landings integral with the side rails cover the edges of the tread belt. The bed is carried on bed rails supported on the side rails by bolts extending through the T-slots into bed slides. Transverse bed supports capped by resilient shock mounts support the center of the bed. Idler and drive rollers at opposite ends of the bed are slidably supported through the T-slots of the side rails on bearing slides. The rear idler roller is adjustably positioned by bolts engaging end caps at the rear ends of the side rails. A motor moves the tread belt over the bed and rollers. An inertial flywheel, fan and encoder wheel are mounted on the motor axle. A linear lift mechanism within the stanchion raises and lowers the treadmill. This reference also indicates that the inertial flywheel is significantly heavier than those found in other exercise treadmills to reduce the peak loads placed on the treadmill's

motor. A fan recessed within the outer surface of the flywheel draws air between the spokes of the flywheel and over the air inlet grill of the motor.

SUMMARY

In one embodiment, an exercise machine includes a deck, a motor housing incorporated into the deck, a console positioned at an elevation above the motor housing, a fan associated with at least one of a lift motor and a drive motor in the motor housing, an airflow pathway extending from a location adjacent the fan through a first outlet vent located in the console to a location above the motor housing, and a mechanism configured to selectively alter airflow flowing through the airflow pathway.

The mechanism may include a clutch coupled with the fan. The clutch may include an electromagnetic clutch.

The clutch may be in a normally engaged state.

The mechanism may include a diverter.

The diverter may be displaceable between at least two different positions, including a first position wherein substantially all airflow is directed through the first outlet vent, and a second position wherein all airflow is directed through a second vent to a location away from the location above the motor housing.

The diverter may be displaceable to at least a third position wherein a first portion of the airflow is directed through the first outlet vent and a second portion of the airflow is directed through the second outlet vent.

The diverter may be placed in the first position upon starting operation of the exercise machine.

The exercise machine may include at least one post member extending from a location adjacent the deck up to the console, and wherein the airflow pathway extends through an interior portion of the at least one post member.

An inlet vent may be located in the at least one post member and be in fluid communication with the airflow pathway.

The exercise machine may include at least one auxiliary fan disposed within the airflow pathway.

The at least one auxiliary fan may be configured to begin operation upon starting operation of the exercise machine.

The exercise machine may include a flywheel where the fan is attached to the flywheel and the fan generates an airflow that directs air across the lift motor.

Generating the airflow may include pushing air towards the lift motor.

Generating the airflow may include drawing air towards the fan assembly.

The exercise machine may include a first pulley incorporated into the deck, a tread belt incorporated into the deck and in engagement with the first pulley, a drive motor in mechanical communication with the first pulley, and the flywheel being rotationally fixed with respect to the drive motor. When the drive motor causes the tread belt to move in a rotational direction and causes the flywheel to spin, the fan assembly directs air across the lift motor.

The exercise machine may include a second pulley incorporated into the deck at an opposite end of the deck than the first pulley, and the tread belt surrounds the first pulley and the second pulley.

The drive motor, flywheel, and fan assembly may be coaxial, and the fan assembly may be located adjacent to the lift motor.

The exercise machine may include a second fan connected to a second side of the flywheel, where the second fan

generates a second airflow when the flywheel rotates, the second airflow being configured to pass over the drive motor.

The exercise machine may include a dump resistor connected to the drive motor where the dump resistor is positioned within the airflow generated with the fan.

The cooling mechanism may include a ring member, an annulus defined in the ring member, and at least one fan blade formed on the ring member.

When the ring member is rotating, a pressure drop may be generated within the annulus.

The exercise machine may include an annular lip formed on the circumference of the ring member and adjacent to the fan blade.

The exercise machine may include a housing and at least one vent located in a bottom side of the housing where the lift motor and the cooling mechanism are located within the housing.

In one embodiment, a fan assembly includes a ring member, a face of the ring member, an annulus defined in the ring member, and at least one fan blade formed on the face of the ring member.

When the ring member is rotating, a pressure drop may be generated within the annulus.

The fan assembly may include an annular lip formed on the circumference of the ring member and adjacent to the fan blade.

The fan assembly may include the ring member that is attached to a flywheel where a pressure drop pulls intake air towards the annulus and where the flywheel and the annular lip collectively reverse the flow of the intake air away from the annulus at an angle greater than ten degrees with respect to a rotational axis of the ring member.

The fan assembly may be incorporated into a treadmill and directs an airflow across a lift motor.

In one embodiment, a method of operating an exercise machine includes providing a deck with a motor housing, providing a motor in the motor housing to alter an operating characteristic of the deck, providing a fan to circulate air over the motor, providing an airflow pathway from a location adjacent the fan, to a first exhaust vent located in a console of the exercise machine, exhausting substantially all airflow from the fan through the first exhaust vent to a location above the motor housing upon starting the exercise machine, and altering at least one characteristic of the airflow through the airflow pathway during subsequent operation of the exercise machine.

Altering at least one characteristic of the airflow may include turning off the fan.

Altering at least one characteristic of the airflow may include diverting at least a portion of the airflow through a second exhaust vent.

Altering at least one characteristic of the airflow may include diverting substantially all of the airflow through a second exhaust vent.

Altering at least one characteristic of the airflow may be responsive to a user command.

Altering at least one characteristic of the airflow is responsive to a command associated with a predefined workout program or a simulated environment.

In accordance with one embodiment, a treadmill comprises a deck, a motor housing incorporated into the deck, a first pulley incorporated into the deck, a tread belt incorporated into the deck and in engagement with the first pulley, a drive motor located within the motor housing, in mechanical communication with the first pulley, a flywheel being rotationally fixed with respect to the drive motor where the

drive motor causes the tread belt to move in a rotational direction and causes the flywheel to spin, a lift motor located in the motor housing, a fan assembly that cools the lift motor, a console, at least one post member extending from a location adjacent the deck to the console, an airflow path extending from the fan, through the at least one post member, through an exhaust vent located in the console, and a mechanism configured to selectively alter airflow flowing through the airflow pathway.

BRIEF DESCRIPTION OF THE DRAWINGS

FIG. 1 depicts an example of an exercise machine in accordance with aspects of the present disclosure.

FIG. 2 depicts an example of an exercise machine in accordance with aspects of the present disclosure.

FIG. 3 depicts an example of a cooling mechanism in accordance with aspects of the present disclosure.

FIG. 4 depicts an example of a cooling mechanism in accordance with aspects of the present disclosure.

FIG. 5 depicts an example of a cooling mechanism in accordance with aspects of the present disclosure.

FIG. 6 depicts an example of a cooling mechanism in accordance with aspects of the present disclosure.

FIG. 7 depicts an example of a cooling mechanism in accordance with aspects of the present disclosure.

FIG. 8 depicts an example of a cooling mechanism in accordance with aspects of the present disclosure.

FIG. 9 depicts an example of a cooling mechanism in accordance with aspects of the present disclosure.

FIGS. 10-12 depict an example of an exercise machine incorporating a cooling system in accordance with aspects of the present disclosure.

DETAILED DESCRIPTION

For purposes of this disclosure, the term "aligned" means parallel, substantially parallel, or forming an angle of less than 35.0 degrees. For purposes of this disclosure, the term "transverse" means perpendicular, substantially perpendicular, or forming an angle between 55.0 and 125.0 degrees. Also, for purposes of this disclosure, the term "length" means the longest dimension of an object. Also, for purposes of this disclosure, the term "width" means the dimension of an object from side to side. Often, the width of an object is transverse the object's length. Additionally, for purposes of this disclosure, the term "post" generally refers to an upright structural member.

FIG. 1 depicts an example of a treadmill 100 having a deck 102 with a first pulley disposed in a front portion of the deck 102 and a second pulley incorporated into a rear portion of the deck 102. A tread belt 104 surrounds the first pulley and the second pulley. A drive motor is in mechanical communication with either the first pulley or the second pulley.

The rear portion of the deck 102 is attached to a base member 106 of the treadmill's frame. A pivot connection 110 between the rear portion of the deck 102 and the base member 106 allows the front portion of the deck 102 to incline upwards or decline downwards. When the deck 102 inclines or declines, the base member 106 remains stationary.

A first side post 112 is attached to a first side of the base member 106, and a second side post 114 is attached to a second side of the base member 106. In the example depicted in FIG. 1, the first side post 112 and the second side post 114 also remain stationary as the deck 102 inclines

and/or declines. The first side post 112 and the second side post 114 collectively support a console 116. The console 116 includes a display 118 and an input mechanism 120 for controlling the deck's incline angle. A vent or other outlet 130 may also be formed in the console 116 and configured to exhaust airflow to a location above the treadmill deck 102 and onto a user during operation of the treadmill 100.

FIG. 2 illustrates an example of a treadmill 202 with a cover removed for illustrative purposes. Inside the cover, a drive motor 204 is disposed adjacent to a pulley 206 that moves the tread belt 208 in a rotational direction. Attached to and coaxial with the drive motor 204 is a flywheel 210. The flywheel 210 rotates with the drive motor 204.

A fan assembly 212 is connected to the flywheel 210 on the flywheel's side that is away from the drive motor 204. The fan assembly 212 is also coaxial with the drive motor 204. A lift motor 214 is adjacent to the fan assembly 212. The lift motor 214 is oriented so that it is connected to the deck 216 and also to the base frame (e.g., 106 in FIG. 1) of the treadmill. When activated, the lift motor 214 causes a rod to extend downward, which pushes against the front portion of the deck and the base frame causing the front portion of the deck to raise. In other situations, when the lift motor 214 is activated, the rod is retracted, which causes the front portion of the deck to lower. In these cases, the lift motor 214 may be transversely oriented with respect to the fan assembly 212.

In some cases, the lift motor 214 is located within inches of the fan assembly 212. In some situations, the lift motor 214 is located less than an inch away from the fan assembly 212. When the drive motor 204 is active, the flywheel 210 and the fan assembly 212 rotate together. The fan assembly 212 causes air to flow around the lift motor 214, which can lower the lift motor's temperature. The other components within the housing may also experience a temperature drop due to the operation of the fan assembly 212.

In some cases, a clutch mechanism 220 mechanism is placed between the flywheel 210 and the fan assembly 212. In some cases, the clutch mechanism 220 is configured to be normally engaged (meaning the fan assembly is coupled with, and rotates with, the flywheel) and can be selectively disengaged. In one example, an input mechanism (e.g., 120 in FIG. 1) may be actuated by a user to selectively disengage and/or reengage the fan assembly 212 with the flywheel 210.

FIG. 3 illustrates an example of a treadmill 300 with a cover removed for illustrative purposes. The treadmill 300 includes a flywheel 302 and a fan assembly 304 attached to the flywheel 302. A lift motor 306 is located adjacent to the fan assembly 304.

In this example, the fan assembly 304 includes a ring member 308 that defines a central annulus 310. Distally located with respect to the central annulus 310, a plurality of fan blades 312 are formed in the ring member's face 314. While any appropriate type of fan blade geometry may be used, the fan blade geometry in this example includes a leading side 316 that forms an edge face that is transversely oriented with a base of the fan assembly 304. A trailing side 318 of the fan blade 312 tapers towards a base of the ring member 308 and towards an adjacent fan blade. A circumferential lip 320 is located on the circumference of the ring member 308. In this example, the circumferential lip has a height that is approximately the height of the leading side 316 of the fan blades 312.

FIG. 4 illustrates an example of the cooling mechanism 400. In this example, the cooling mechanism 400 includes

the drive motor 402, the flywheel 404, and the fan assembly 408. The lift motor 406 is located adjacent to the lift motor 406.

As the drive motor 402 rotates, the flywheel 404 and fan assembly 408 also rotate. As the fan assembly 408 rotates, a pressure drop is generated in the annulus 410 of the ring member. This pressure drop draws air creating an airflow across the lift motor 406. The fan blades of the fan assembly 408 push air outward across the leading sides of the fan blades towards the circumferential lip of the fan blade. The circumferential lip pushes the airflow forward so that the intake air reverses its direction. In some examples, the airflow is rerouted between 120 degrees to 175 degrees from the intake air's initial travel direction.

With the movement of the air generated by the fan assembly, a pressure drop may be generated behind the fan assembly and adjacent the flywheel 404. In this example, the air from behind the fan assembly 408 may be drawn into the airflow and increase the air circulation in the entire housing. Vent openings 412 may be formed in the bottom portion 414 of the housing to increase an air exchange between the inside and outside of the motor housing.

FIG. 5 illustrates an example of a cooling mechanism 500. In this example, the cooling mechanism includes an annulus 502 centrally located within the ring member 504. A plurality of fan blades 506 are distally located on the annulus 502. Each of the fan blades 506 includes a leading side 508 and a trailing side 510. The leading side 508 includes an edge face that extends from a base of the ring member 504. The trailing side 510 of the fan blade progressively tapers towards an adjacent fan blade and towards the base of the ring member 504. A circumferential lip 512 is disposed distally to the fan blades 506 and includes a height that is substantially the height of the blades' edge face.

FIG. 6 illustrates an example of a cooling mechanism 600. In this example, the cooling mechanism 600 includes a ring member 602 with a fan face 604. A plurality of fan blades 606 are formed in the fan face 604. The fan blades 606 span the fan face from an outer ring diameter 608 to an inner ring diameter 610. Each fan blade 606 includes a leading side 612, a distal side 614, a trailing side 616, and a proximal side 618. In this example, the distal side 614 of the fan blades is forward of the proximal side 618. Additionally, the cross sectional thickness of the fan blade at the distal side 614 is greater than the fan blade's cross sectional thickness at the proximal side 618. The leading side 612 of the fan blade 606 has a slightly concave surface and the trailing side 616 has a slightly convex surface. In this example, the ring member 602 does not include a circumferential lip.

FIG. 7 illustrates an example of a cooling mechanism 700. In this example, the ring member 702 includes a plurality of fan blades 704 spaced along the ring's fan face 706. The ring member 702 includes an inner diameter defined by an annulus 708 in the ring member 702. An inner circumferential lip 710 is located on the inner diameter 712 which is integrally formed with the proximal sides 714 of the fan blades 704.

FIG. 8 illustrates an example of a cooling mechanism 800. In this example, the cooling mechanism 800 includes a flywheel 802 with a first side 804 and a second side 806 opposite the first side 804. A first fan assembly 808 may be attached to the first side 804, and a second fan assembly 810 may be attached to the second side 806. As the flywheel 802 rotates, the first fan assembly 808 and the second fan assembly 810 may rotate simultaneously causing separate airflows to be generated. In some cases, the lift motor may be primarily cooled by an airflow generated by the first fan

assembly **808** and the drive motor may be primarily cooled by an airflow generated by the second fan assembly **810**.

FIG. 9 illustrates an example of a cooling mechanism **900** in a treadmill **902**. In this example, a dump resistor **904** is located within the housing **906**. The dump resistor **904** may be used to dissipate unneeded electricity in the system. In some cases, the drive motor **908** may be the source of unneeded electricity. For example, in some cases the load on the motor is progressively reduced as the incline on the deck increases because the user's body weight contributes to moving the tread belt. At some incline angles, the user's body weight may generate all the force necessary to move the tread belt, so that there is no load on the drive motor. But, at even steeper incline angles, the user's body weight moves the tread belt, which correspondingly moves the pulley and therefore the drive motor **908** to the point where the drive motor **908** generates electricity. This generated electricity may be directed to the dump resistor **904** which converts the unneeded electricity into heat. The dissipated heat increases the temperature in the housing. The fan assembly **910** may be used to cool the interior of the housing.

FIGS. 10-12 illustrate a treadmill **1000** that includes an airflow channel **1002** directing air from a fan (e.g., fan assembly **212** of FIG. 2) to one or more specified exhaust ports or vents **1006**, **1020**. In one example, an air channel **1002** is formed within one or both posts **1008** of the treadmill **1000** up into an internal area associated with the console **1010**. Thus, airflow that is generated by a lift-motor (or other) fan assembly located within the shroud or cover **1012** (e.g., the cover associated with the drive and lift mechanisms) is directed to the console **1010** and exits through one or more of the exhaust vents **1006**, **1020**. While one exhaust vent **1020** is shown on the post **1008** of the treadmill **1000**, any number of exhaust vents **1020** may be formed in the post to exhaust the airflow originating in the shroud or cover **1012**.

As seen in FIG. 10, air generated by a fan within the cover **1012** can be directed through the post(s) **1008**, in the direction towards the console **1010**, but out a vent **1020** located in the posts such that the airflow exhausts at a location over the deck **1014** of the treadmill **1000**. In the example shown in FIG. 10, the direction of the air through the vent **1020** in the posts is effected by positioning a damper or airflow damper or diverter **1016** to a first position that blocks air flow through the console.

FIG. 11 depicts an example of an auxiliary fan **1022** located in the posts that forces air out of the vent **1020** in the posts. In this example, the airflow diverter **1016** is closed off to the vent **1006** in the console **1010**, which forces the air out of the posts.

When the airflow diverter **1016** is changed to a second position, such as shown in FIG. 12, airflow generated within the cover **1012** may be directed through the post(s) **1008**, into the console **1010**, and out a rear facing vent **1006**. While the airflow diverter is shown in a specific position, the diverter **1016** may be adjusted to a variety of positions to afford varying levels of airflow above the deck **1014** and blowing out the console.

In some cases, the airflow diverter may be coupled with an actuator to displace the diverter between its various positions. The actuator may be controlled by a user of the treadmill using an input device or mechanism (e.g., **120** of FIG. 1). In other cases, the actuator may be controlled by a program to control the airflow exiting above the deck and onto a user in accordance with a desired exercise program or to correspond with an intensity of the workout experienced

by the user (e.g., higher running speeds and/or larger inclines may correspond to a higher airflow from the front vent).

In some cases, the airflow diverter **1016** may be positioned as shown in FIG. 10 upon starting operation of the treadmill, such that all of the airflow initially exhausts through the vent **1020** in the post **1008**. A user may then adjust the airflow as desired. In some cases, the airflow diverter may start in the position shown in FIG. 10, and then 10 a control program of the treadmill may alter its position depending on one or more operating characteristics of the treadmill **1000**.

In some examples, the console may include a separate fan that is used to direct air towards the user. This fan may pull 15 air from sources outside of the motor housing or other components of the treadmill. For example, this fan may pull air from the ambient environment. As illustrated in FIGS. 10-12, the one or more auxiliary fans **1022** are positioned in the air channel **1002** on each post **1008** and exhausted to the 20 rear of the treadmill **1000** away from a user. Thus, the air pulled by the console fan is taken substantially from the ambient environment, rather than from the air that has been heated from the operation of the treadmill and exhausted through the vent **1020**. In some cases, one or more auxiliary fan **1022** may be positioned at other locations in the airflow path to further enhance circulation of the airflow from the 25 area within the cover **1012** up to the vents **1006**. Such fans **1022** may be positioned in the posts **1008** in the console, or at any other point within the flow path.

In some cases, the flow path may be directed within the 30 console to cool additional components prior to being exhausted through one or more vents **1006**, **1020**. For example, the airflow path may traverse a control board, a processor, or other electronic components to remove heat from such components prior to being exhausted from the console.

While the examples above have been described with the 35 outlet being located in the console, the outlet may be located in other areas of the treadmill that are above the deck. For example, outlets may be located within the posts that support the console. Diverters and other components to direct the air flow may direct the air flow out the outlets of the posts and/or console as instructed by the user.

GENERAL DESCRIPTION

In general, various embodiments according to the present disclosure may provide users with an exercise machine that can cool its internal components during the performance of an exercise. In some cases, a workout program may involve raising and lowering the deck. Each time that the deck is moved upwards or downwards, a demand is made on the lift motor. Lift motors are not generally used continuously throughout a workout. Typically, an exercise program performed on a treadmill involves moving the deck to an incline and keeping the deck at that angle. But, the lift motor may generate heat as it is used. In some cases, when the lift motor increases its temperature, the components around the lift motor may also experience an elevated temperature. Thus, 55 the lift motor may increase the temperature of the exercise machine's other components, which can negatively impact their performance as well. Under some conditions, the heat generated in the lift motor degrades the seals, fluids, and other lift motor components.

60 The cooling mechanisms and systems described herein may be used to lower the temperature of the lift motor and/or other components of the treadmill. Additionally, the cooling

mechanisms and systems herein may be associated with a flow path that provides cooling of the treadmill.

A treadmill includes a deck which may further include a first pulley located in a front portion of the deck and a second pulley located in a rear portion of the deck. A tread belt may surround the first and second pulleys and provide a surface on which the user may exercise. At least one of the first pulley and the second pulley may be connected to a drive motor so that when the drive motor is active, the pulley rotates. As the pulley rotates, the tread belt moves as well. The user may exercise by walking, running, or cycling on the tread belt's moving surface.

The deck may be capable of having its front portion raised and lowered as well as its rear portion raised and lowered to control the lengthwise slope of the running deck. With these elevation controls, the orientation of the running deck can be adjusted as desired by the user or as instructed by a programmed workout. In those examples where the treadmill is involved with simulating a route that involves changes in elevation, the running deck can be oriented to mimic the elevation changes in the route while the user performs an exercise on the deck.

In one example, the lengthwise slope and/or lateral tilt angle of the deck can be controlled with one or more lift motors. In one example, a single lift motor connects the deck and the exercise machine's base. In this example, when the single lift motor extends a rod, the deck's incline angle increases and when the lift motor retracts the rod, the deck's incline angle decreases.

Any appropriate trigger may be used to cause the lift motor to change the deck's incline angle. In some cases, the incline angle is changed in response to an input from the user, a simulated environment, a programmed workout, a remote device, another type of device or program, or combinations thereof.

In some cases, the exercise machine includes a console attached to an upright structure. In some cases, the upright structure includes a first post adjacent to a first side of the deck and a second post adjacent to a second side of the deck. In this example, the console is supported by the first and second post. The deck moves independently of the first and second posts and also moves independently of the console. In other examples, the posts may move with the deck as the deck's incline angle changes.

The console may locate a display screen and the treadmill's controls within a convenient reach of the user to control the operating parameters of the treadmill. For example, the console may include controls to adjust the speed of the tread belt, adjust a volume of a speaker integrated into the treadmill, adjust an incline angle of the running deck, adjust a decline of the running deck, adjust a lateral tilt of the running deck, select an exercise setting, control a timer, change a view on a display of the console, monitor the user's heart rate or other physiological parameters during the workout, perform other tasks, or combinations thereof. Buttons, levers, touch screens, voice commands, or other mechanisms may be incorporated into the console and can be used to control the capabilities mentioned above. Information relating to these functions may be presented to the user through the display. For example, a calorie count, a timer, a distance, a selected program, an incline angle, a decline angle, a lateral tilt angle, another type of information, or combinations thereof may be presented to the user through the display.

The treadmill may include preprogrammed workouts that simulate an outdoor route. In other examples, the treadmill has the capability of depicting a real world route. For

example, the user may input instructions through the control console, a mobile device, another type of device, or combinations thereof to select a course from a map. This map may be a map of real world roads, mountain sides, hiking trails, beaches, golf courses, scenic destinations, other types of locations with real world routes, or combinations thereof. In response to the user's selection, the display of the control console may visually depict the beginning of the selected route. The user may observe details about the location, such as the route's terrain and scenery. In some examples, the display presents a video or a still frame taken of the selected area that represents how the route looked when the video was taken. In other examples, the video or still frame is modified in the display to account for changes to the route's location, such as real time weather, recent construction, and so forth. Further, the display may also add simulated features to the display, such as simulated vehicular traffic, simulated flora, simulated fauna, simulated spectators, simulated competitors, or other types of simulated features. While the various types of routes have been described as being presented through the display of the control console, the route may be presented through another type of display, such as a home entertainment system, a nearby television, a mobile device, another type of display, or combinations thereof.

In addition to simulating the route through a visual presentation of a display, the treadmill may also modify the orientation of the running deck to match the inclines and slopes of the route. For example, if the beginning of the simulated route is on an uphill slope, the running deck may be caused to alter its orientation to raise the front portion of the running deck. Likewise, if the beginning of the simulated route is on a downward slope, the rear portion of the running deck may be caused to elevate to simulate the decline in the route.

Also, if the route has a lateral tilt angle, the running deck may be tilted laterally to the appropriate side of the running deck to mimic the lateral tilt angle.

While the programmed workout or the simulated environment may send control signals to orient the deck, the user may, in some instances, override these programmed control signals by manually inputting controls through the console. For example, if the programmed workout or the simulated environment cause the deck to be steeper than the user desires, the user can adjust the deck's orientation with the controls in the console.

Any appropriate type of lift motor may be used in accordance with the principles described herein. For example, a non-exhaustive list of lift motors that may be used includes screw motors, linear actuators, hydraulic motors, pneumatic motors, solenoids, electro-mechanical motors, other types of lift motors, or combinations thereof. Further, the lift motor may be powered with compressed gas, electricity, magnetic fields, other types of power sources, or combinations thereof. Further, the lift motors may also have the ability to laterally tilt the running deck to any appropriate angle formed between a running surface of the running deck and the surface upon which the treadmill rests. For example, the range of the lateral tilt angle may span from negative 55 degrees to positive 55 degrees or any range there between.

Any appropriate type of drive motor may be used to drive the tread belt in a rotational direction. In some examples, the drive motor may be an alternating current motor that draws power from an alternating power source, such as the power circuit of a building. In some cases, the drive motor is a direct current motor. In some of the examples with a direct

11

current motor, the direct current motor draws power from a building power circuit, but the alternating current is converted to direct current.

A flywheel may be connected to a portion of the drive motor so that the flywheel rotates when the drive motor is active. The flywheel may store rotational energy and assist with moving the tread belt at a consistent speed. In some examples, the flywheel has a common rotational axis with the drive motor. In these examples, the flywheel may be connected to the drive motor with an axle. In other situations, the flywheel is attached directly to a side of the drive motor. The flywheel may include any appropriate size, shape, length, width, and weight in accordance with the principles described herein.

The lift motor may operate independent of the drive motor. In some examples, the lift motor may be active when the drive motor is dormant. In other situations, the drive motor may be active when the lift motor is dormant. In some situations, the lift motor and the drive motor may be operated simultaneously, but driven in response to different command sources.

In some cases, the drive motor, flywheel, and the lift motor reside within a common housing. The housing may be incorporated into the deck adjacent to at least one of the motors. In some cases, a lift motor is incorporated in the front portion of the deck, and the housing is located in the front housing of the deck. In other examples, a lift motor is incorporated into a rear portion of the deck, and the housing is incorporated in the rear portion of the deck. In other examples, deck includes a lift motor in the front portion of the deck and in the rear portion of the deck where the elevation of the front and rear portions of the deck can be controlled independently.

As previously noted, the temperature of the lift motor may increase based on continued use or from other causes. A cooling mechanism may be incorporated into the housing to lower the internal temperature of the housing and/or lower the lift motor's temperature. In some examples, the cooling mechanism includes a fan assembly that is attached to the flywheel.

Any appropriate type of fan assembly may be used in accordance with the principles described in the present disclosure. In one example, the fan assembly includes a ring member that defines a central annulus. The ring member may include a fan face and an attachment face opposite of the fan face. The attachment face may connect to the flywheel, and a fan blade may be formed on the fan face. In some examples, the fan blade includes a geometry that forces air to move in response to the rotation of the ring element. In some cases, the fan blades are protrusions that extend beyond the fan face. These blades may include any appropriate type of shape including, but not limited to, a generally rectangular shape, a generally crescent shape, a generally square shape, another general shape, or combinations thereof. In some cases, the blade generates lift, which causes the high and low pressure regions of the air in the immediate vicinity of the blade as the ring element rotates.

In some cases, the ring element includes a lip that protrudes from the fan face's edge and extends away from the fan face in the same direction as the fan blade extends from the fan face. The lip may extend away from the fan face at the same distance as the fan blades. In some cases, the circumferential lip may extend away from the fan face at a greater distance than the fan blade. In yet other examples, the fan blades may extend from the fan face at a greater distance than the lip extends. The lip may contribute to directing the airflow generated by the fan assembly.

12

In some examples, a low pressure region is generated within the annulus of the ring element when the fan assembly rotates. As a result, air is pulled into the annulus. In those examples where the ring member is attached to the side of the flywheel, the flywheel blocks air from traveling through the annulus which focuses the airflow to the side. The shape of the fan blades may also direct the airflow to the side. The air that is directed to the ring member's side is forced forward of the fan face as the air moves towards the lip attached to the ring's circumferential edge. The lip blocks the air from flowing directly off of the ring element's side. Thus, the airflow that is pulled towards the annulus of the ring member is rerouted to move in an opposing direction. In some cases, the airflow is rerouted 180 degrees. In some examples, the airflow is rerouted between 120 degrees to 175 degrees. The redirected airflow may be contained within the housing. As the redirected airflow travels off of the fan face at an angle, the airflow may generate low pressure regions behind the fan assembly. These low pressure regions may cause air to flow within other regions within the housing.

In other examples, the ring member includes a fan face without the circumferential lip. In these examples, the airflow may exit the fan face directly off of the ring member's side. Initial testing shows that those ring members with a circumferential lip on the ring's outer diameter result in a fifty percent noise reduction than those ring members without a circumferential lip.

The lift motor may be located on the fan side of the ring member within the housing. Thus, when the flywheel rotates, the fan assembly may draw in air into the annulus so that air is pulled across the lift motor. As a result, the airflow may remove heat from the lift motor. In other examples, the lift motor may be located elsewhere within the housing and the entire interior of the housing may be lowered as a result of the fan assembly's operation. In some cases, the housing may include vent openings that allow hot air to exit the housing and cool air to be drawn into the housing. The vent openings may be located on an underside of the housing to prevent sweat, liquid, debris, or other substances from falling into the vent holes.

The cooling mechanism as described herein may lower the temperature of the machine's components located within the housing. In particular, the fan assembly may be oriented to generate an airflow across the lift motor to cool the lift motor. Lowering the temperature of the lift motor may reduce the rate of degradation of the lift motor's seals, fluids, and other components. Further, initial testing of cooling mechanisms as described herein have lowered the temperature of the internal housing by 20 degrees Celsius. Another benefit to the cooling mechanism as described herein is the effective temperature differential in a tight space that cannot accommodate bulky or large cooling assemblies.

While the examples above have been described with reference to cooling the lift motor, the cooling mechanism may be used to cool other exercise machine components in addition to or in lieu of the lift motor. For example, some exercise machines may include a printed circuit board with cooling fins. The increased airflow may make the fins of the printed circuit board remove heat more effectively.

In some examples, the load on the drive motor diminishes as the incline of the deck increases. As the incline angle of the deck increases, the user's body weight pushes the tread belt down the length of the deck. In some cases, when the deck's incline angle reaches 12 degrees, the user's body weight is sufficient to drive movement of the tread belt. This can cause the electric motor to operate in reserve causing the

motor to generate electricity. The generated electricity can be directed to a dump resistor where the electricity is converted into heat. In examples where the dump resistor is located within the housing, the fan assembly may direct an airflow across the dump resistor to remove the resistor's heat. In some cases, the dump resistor may have a coiled geometry. In other examples, the dump resistor may have a flat geometry with multiple turns. Regardless of the dump resistor's geometry, the increased airflow across the resistor's surface may reduce the resistor's temperature.

In some examples, the flywheel is connected to multiple fan assemblies. For example, a first fan assembly may be connected to a first side of the flywheel, and a second fan assembly may be connected to a second side of the flywheel that is opposite of the first side. The first fan assembly may generate a first airflow that causes air to pass through the lift motor while the second fan assembly may generate a second airflow that causes air to pass through the drive motor which may lower the temperature of the drive motor. In other examples, additional fan assemblies may be connected to the flywheel with an axle. In this type of example, the fan assemblies may be connected in series and be spaced apart from each other.

In some cases, the fan assembly is attached to the flywheel. In other examples, the fan assembly is integrally formed in the flywheel. Further, in some cases, the fan assembly is attached to the side of the flywheel. In yet other examples, the fan assembly is disposed about the circumference of the flywheel.

In some examples, the fan assembly may be a centrifugal fan where the fan assembly includes an impeller that includes a series of blades. The fan assembly blows air at right angles to the intake of the fan through a centrifugal force.

In some examples, a clutch mechanism may be installed between the flywheel and the fan, enabling selective disengagement of the fan from the flywheel. Thus, even though the flywheel may be rotating, if the clutch is not engaged, the fan will not rotate with the flywheel. In some embodiments, the clutch may include an electromagnetic clutch. In some embodiments, the clutch may be configured in a "normally engaged" status, meaning that the fan is engaged with the flywheel and rotates with the flywheel when operation of the treadmill is started. The clutch may then stay in the engaged status until it is selectively disengaged.

Any appropriate trigger may be used to cause disengagement of the clutch. In some cases, the clutch is disengaged in response to an input from the user, a simulated environment, a programmed workout, a remote device, another type of device or program, or combinations thereof. Likewise, any appropriate trigger, such as those noted above, may be used to cause reengagement of the clutch.

An airflow path may be provided from the area associated with the fan (e.g., the area within the shroud or cover and associated with the drive motor and/or lift mechanism) to exhaust the airflow to a desired location. In some embodiments, an airflow path may be provided from a location adjacent a fan assembly to the console, and through one or more exhaust or outlet vents. In some embodiments, an exhaust vent may be configured to direct some or all of the airflow exhaust to a location directly above the deck of the treadmill to blow on, and cool, a user of the treadmill.

In some embodiments, multiple exhaust vents may be utilized. An airflow diverter may be used to proportion the amount of airflow exhausting from each vent. In some embodiments, the airflow diverter may be used to selectively and completely divert the airflow solely to any one of the

exhaust vents. For example, when the airflow diverter is in one selected position, it may direct all airflow such that exhausts above the treadmill deck as noted above. When the airflow diverter is in a second position, it may direct a portion of the airflow above the deck, and direct a portion to another location (not above the deck) and away from the user. When the airflow diverter is in a third position, it may direct all airflow to exhaust to a location away from the deck and user of the treadmill. The flow diverter may be infinitely adjustable to provide a variety of adjustment levels to the airflow exhausting above the deck.

In some embodiments, the cooling system, including software instructions, is arranged such that the auxiliary fan runs and all of the airflow is exhausted through the back side of the console above the deck upon starting operation of the treadmill. Thus, the diverter may be initially positioned, upon each operational start of the treadmill, to divert all airflow through one or more exhaust vents to a location above the deck away from the user. A user may then manually adjust the diverter to alter the airflow if desired. Alternatively, or additionally, other triggers may alter the position of the diverter after operation of the treadmill has started. Such triggers may include, for example, a simulated environment, a programmed workout, a remote device, another type of device or program, or combinations thereof.

In some embodiments, the airflow channel may include a pathway through one or more posts of the treadmill up to the console. In some embodiments, inlet vents may be placed in the posts, or at any other location along the airflow path, to enable ambient air to be drawn into the airflow channel and mix with air that is being drawn across the lift motor, drive motor or other related components. The mixture of ambient air may provide some cooling to the air drawn from within the shrouded or covered area prior to exhausting through the back side of the console.

In some embodiments, one or more auxiliary fans, such as an electric fan, may be placed at another location within the airflow path. For example, an auxiliary fan may be placed in a post (or one in each post), within the console, or at some other location. The auxiliary fan may be configured to operate in conjunction with the fan assembly coupled with the flywheel (e.g., turn on when the clutch is engaged, and off when the clutch is disengaged), or operate independent from the fan assembly. In one embodiment, the auxiliary fan or fans may be configured to start when the treadmill is started by a user for operation. In some embodiments, a user may then manually turn off the auxiliary fan(s). Alternatively, or additionally, other triggers may alter the operation of the auxiliary fan(s) after operation of the treadmill has started. Such triggers may include, for example, a simulated environment, a programmed workout, a remote device, another type of device or program, or combinations thereof.

In some embodiments, the airflow path may be defined to provide cooling to additional components of the treadmill. For example, the airflow path may be arranged such that air flows over, and provides cooling to, control boards, processors, displays, or other electronic components, including those associated with the console.

While the examples above describe a cooling mechanism that can be used in relation to a treadmill, the cooling mechanism may be used in any appropriate type of exercise machine. For example, the fan assembly may be attached to the flywheel of a resistance mechanism. In these types of examples, the resistance mechanisms may be incorporated into stationary bikes, elliptical trainers, rowing machines, or other types of exercise machines. The fan assemblies may be used to cool the components of the exercise machine. These

15

component may include motors, lift motors, dump resistors, electronics, bearings, sensors, other types of components, or combinations thereof.

The description herein is provided to enable a person skilled in the art to make or use the disclosure. Various modifications to the disclosure will be readily apparent to those skilled in the art, and the generic principles defined herein may be applied to other variations without departing from the scope of the disclosure. Thus, the disclosure is not limited to the examples described herein, but is to be accorded the broadest scope consistent with the principles and novel features disclosed herein.

What is claimed is:

1. An exercise machine comprising:
a deck;
a motor housing incorporated into the deck;
a console positioned at an elevation above the motor housing;
a fan associated with at least one of a lift motor and a drive motor located in the motor housing;
an airflow pathway extending from a location adjacent the fan through a first outlet vent located in a location above the motor housing; and
a mechanism configured to selectively alter airflow flowing through the airflow pathway.
2. The exercise machine of claim 1, wherein the mechanism includes a clutch coupled with the fan.
3. The exercise machine of claim 2, wherein the clutch includes an electromagnetic clutch.
4. The exercise machine of claim 3, wherein the clutch is in a normally engaged state.
5. The exercise machine of claim 1, wherein the mechanism includes a diverter.
6. The exercise machine of claim 5, wherein the diverter is displaceable between at least two different positions, including a first position wherein substantially all airflow is directed through the first outlet vent, and a second position wherein all airflow is directed through a second vent to a location away from the location above the motor housing.
7. The exercise machine of claim 6, wherein the diverter is displaceable to at least a third position wherein a first portion of the airflow is directed through the first outlet vent and a second portion of the airflow is directed through the second outlet vent.
8. The exercise machine of claim 5, wherein the diverter is in the first position upon starting operation of the exercise machine.
9. The exercise machine of claim 1, further comprising at least one post member extending from a location adjacent the deck up to the console, and wherein the airflow pathway extends through an interior portion of the at least one post member.
10. The exercise machine of claim 9, further comprising an inlet vent formed in the at least one post member and in fluid communication with the airflow pathway.
11. The exercise machine of claim 1, further comprising at least one auxiliary fan disposed within the airflow pathway.

16

12. The exercise machine of claim 11, wherein the at least one auxiliary fan is configured to begin operation upon starting operation of the exercise machine.

13. A method of operating an exercise machine, the method comprising:

providing a deck with a motor housing;
providing a motor in the motor housing to alter an operating characteristic of the deck;
providing a fan to circulate air over the motor;
providing an airflow pathway from a location adjacent the fan, to a first exhaust vent located in a console of the exercise machine;
exhausting substantially all airflow from the fan through the first exhaust vent to a location above the motor housing upon starting the exercise machine;
altering at least one characteristic of the airflow through the airflow pathway during subsequent operation of the exercise machine.

14. The method according to claim 13, wherein altering at least one characteristic of the airflow includes turning off the fan.

15. The method according to claim 13, wherein altering at least one characteristic of the airflow includes diverting at least a portion of the airflow through a second exhaust vent.

16. The method according to claim 13, wherein altering at least one characteristic of the airflow includes diverting substantially all of the airflow through a second exhaust vent.

17. The method according to claim 13, wherein altering at least one characteristic of the airflow is responsive to a user command.

18. The method according to claim 13, wherein altering at least one characteristic of the airflow is responsive to a command associated with a predefined workout program.

19. A treadmill, comprising:
a deck;
a motor housing incorporated into the deck;
a first pulley incorporated into the deck;
a tread belt incorporated into the deck and in engagement with the first pulley;
a drive motor located within the motor housing in mechanical communication with the first pulley;
a flywheel being rotationally fixed with respect to the drive motor where the drive motor causes the tread belt to move in a rotational direction and causes the flywheel to spin;
a lift motor located within the motor housing;
a fan assembly that cools the lift motor;
a console;
at least one post member extending from a location adjacent the deck to the console;
an airflow path extending from the fan, through the at least one post member, through an exhaust vent located in the console; and
a mechanism configured to selectively alter airflow flowing through the airflow pathway.

* * * * *
